UNITED STATES PATENT OFFICE.

ARTHUR E. RIDEOUT, OF CHICAGO, ILLINOIS, ASSIGNOR TO NATIONAL BINDING
MACHINE COMPANY, A CORPORATION OF NEW YORK.

WORK-HOLDER FOR THE SEALING OF CARTONS.

1,310,580.

Specification of Letters Patent. Patented July 22, 1919.

Application filed June 10, 1914, Serial No. 844,137. Renewed December 17, 1918. Serial No. 267,212.

To all whom it may concern:

Be it known that I, ARTHUR E. RIDEOUT, a citizen of the United States, and a resident of Chicago, in Cook county and State of Illinois, have invented an Improvement in Work-Holders for the Sealing of Cartons, of which the following description, in connection with the accompanying drawings, is a specification, like letters on the drawings 10 representing like parts.

This invention relates to a work holder or bench to be used in connection with the sealing of fiber cartons or the like, which operation comprises the preparation of cartons for packing with goods to be shipped therein and the final closure of these cartons after packing and preparatory to shipment. This invention, hereinafter described, 15 consists in a new form of bench, the first arrangement being adapted for use when making up cartons preparatory to packing and the second arrangement for use when finally sealing the cartons so packed.

In carrying out this invention means are 20 provided for the support of a gummed tape moistening machine from which moistened adhesive tape is drawn to be applied to the cartons. The same means also support a supply of liquid adhesive, and further form 25 a convenient support for a pair of weights used in the sealing operation. Means are also provided adjacent the first named means for holding the carton to be sealed, said means consisting of adjustable stands 30 integral with the bench and so constructed that regardless of the size of the carton placed thereon a fixed relation will be maintained between the cartons and the bench. The objects of this arrangement as above 35

40 outlined are to so correlate the various parts that cartons may be sealed with a minimum of time and labor, that the bench may be adjustable in order to accommodate different sized cartons, that the sealing may be 45 accomplished without waste of tape used, and that certain shipping requirements, hereinafter referred to, may be easily complied with.

Numerous efficient devices have been 50 developed for moistening and delivering adhesive strips for sealing boxes or cartons but the work of sealing such cartons is greatly hindered through lack of any efficient device for holding the cartons while 55 being sealed. Where a great number of car-

tons are sealed a slight delay on each carton, in handling and in applying the paste and tape constitutes a serious objection to the use of this method of packing and shipping goods. To overcome the difficulties 60 suggested, the present construction has been devised. I am aware that heretofore a stand provided with a series of interchangeable tops has been used over which cartons are made up ready for packing. My invention 65 contemplates the improvement of such a stand and the provision of further means to be used therewith.

For purposes of illustration I have selected and shown one embodiment of my invention in the accompanying drawings, in which,

Figure 1 is a perspective of a bench constructed in accordance with the present invention, a carton being shown thereon in 75 outline, the arrangement in this figure being adapted for making up cartons preparatory to packing;

Fig. 2 is a plan of three interchangeable tops or heads, showing the means of attachment to the stand member of the bench;

Fig. 3 is a plan top view of a bench as in Fig. 1, showing the relation of the various parts and the interchangeable tops or heads in outline.

Fig. 4 is a perspective of a bench adapted 80 for use when finally sealing the packed cartons preparatory to shipment;

Fig. 5 is a plan top view of the form of bench as in Fig. 4, this figure showing the 90 relation of the various parts; and

Fig. 6 is a detail of means for adjusting a cross bar or stop on the bench shown in Fig. 1.

Referring to the drawings, it will be seen 95 that the improved bench, called in the trade a sealing bench, consists of a stationary L-shaped top member *a* supported from the floor by legs *b* at a height which will prove most convenient for the operator. It has 100 been found by experiment that a height of thirty-five inches will enable the operator to work efficiently. A machine *c* for delivering gummed tape, moistened and ready to apply, is mounted upon the short arm of the 105 L-shaped bench. The long arm of the L-shaped bench forms a convenient support for a pair of weights *d* which are used in the sealing operation and at the extremity of this long arm a paste pot *e* is located.

Adjacent to the L-shaped bench and permanently fastened thereto by suitable means is a stand *f* adapted to hold the carton to be sealed. In the form of the present invention adapted for use when making up the bottoms of the cartons this stand (as in Figs. 1 to 3 inclusive) consists of two uprights *g* suitably braced and joined at the top. Means are provided on the top of this stand for securing varying sized interchangeable tops or heads thereto, the said means being herein shown as a cleat *h*. Top pieces or heads *i*, *j* and *k* (Fig. 2), adapted to be secured to the stand are provided for each size of carton to be sealed. These top pieces have means of attachment corresponding to the means of attachment on the stand, said means being shown herein as cleats *l* adapted to interlock with the cleat *h*. It is important that each top as it is placed upon the stand have a fixed relation to the long and short arms of the L-bench, for purposes hereinafter mentioned. This result is accomplished by placing the cleats *l* upon the top pieces *i*, *j* and *k* with reference only to the sides *m* and *n* of each top. This in turn insures the proper positioning of each top with relation to the long and short arms of the L-bench. The cleats *h* and *l* are so constructed with reference to the height of the stand as to bring the tops to a level with the L-shaped bench.

In the form of the stand member *f* shown in Figs. 1 to 3 inclusive, a stop *o* in the form of a cross bar is provided and is made adjustable in relation to the top of the stand member *f*. This adjustment is accomplished by making the cross bar *o* movable in vertical slots *p* in the end members *g* of the stand and it may be positioned at any given point by means of a series of notches *q* at the side of each slot, and teeth *r* on the cross bar. The notches and teeth are held in engagement by means of a spring lever mechanism consisting of a lever *s* pressed against the side of the slot opposite the teeth by a coiled spring *t*. It is obvious that means other than the means herein shown may be employed to accomplish this adjustment. The purpose of providing this stop or cross bar *o* will be apparent from a description of the use of this bench, hereinafter given.

In the second arrangement of a bench embodying the present invention, shown in Figs. 4 and 5, the L-shaped bench remains the same but the stand *f* is made in the form of a plain shelf for the purpose of holding a packed carton during the operation of finally closing and sealing the same. This bench or shelf *u* is made adjustable with reference to the top of the L-shaped bench, means of adjustment being herein shown as hollow posts *v*, stationary with respect to the main bench, and posts *w* attached to the shelf *u* and slideable in the hollow posts *v*.

By means of winged bolts threaded in the posts *v* and adapted to bear upon the posts *w* the shelf may be secured in any desired position. This position will be such as will bring the top of the box to be sealed to a level with the top of the L-bench. In order that the box to be sealed may be quickly positioned upon the shelf *u* two cleats *y* and *z* are attached to the shelf *u* as shown in Fig. 5. These cleats, against which the box or carton is placed, are arranged to position the carton at distances of four and five inches respectively from the long and short arms of the L-bench.

Fiber cartons are delivered to the user collapsed and before packing goods therein it is first necessary to make up the bottoms of the cartons. When the improved bench herein shown is used in connection with this work the operation consists in first selecting one of the interchangeable tops which will fit exactly inside the expanded carton. The top selected is then placed on the stand member *f* (Figs. 1 to 3) and held thereon by the cleats *h* and *l*. The carton blank is then slipped down over the stand *f* and the stop or cross bar *o* so adjusted that the flaps of the open end of the box will rest thereon and support the carton, as shown in Fig. 1. It will be seen that this stop or cross bar *o*, having been adjusted to the first carton of a number of the same size to be sealed, will automatically position all subsequent cartons of that size. The flaps of the carton which will form the bottom thereof are then folded down upon the top of the stand. Liquid adhesive is applied between these flaps and the weights *d* are placed thereon crosswise of the box to hold the flaps together while the paste is drying. Strips of adhesive tape are drawn from the gummed tape supplying machine *c* and pasted crosswise of the box at the ends and in the center. The weights are then placed parallel to the center seam of the bottom of the box and another strip of adhesive tape is pasted length-wise of the box over this center seam.

Transportation companies require that the tape used in sealing these cartons shall overlap the sides of the carton two and one half inches. To comply with this requirement the cleats *h* and *l* and the stand *f* are so arranged that each of the interchangeable tops will be positioned exactly five inches from the short arm of the L-shaped bench. It will thus be apparent that if the strip is drawn from the machine *c* to the farther end of the carton and then cut off at the machine just enough extra tape will be provided to take care of this overlap. This permits the operator to seal each carton easily and quickly and without waste of tape.

When the cartons are packed and ready to be finally closed preparatory to shipment

the form of the stand *f* shown in Figs. 4 and 5 is used, and its use in this connection consists in first adjusting the shelf *u* so that the top of the cartons to be placed thereon will be on a level with the top of the L-shaped bench. The carton to be sealed is then placed upon the shelf and pushed into the corner formed by the cleats *y* and *z*. Paste is applied to the flaps of the carton and they are folded down and pressed together. The weights *d* are placed thereon to hold the flaps while the paste is drying. As pointed out in connection with the making up of the bottom of the carton strips of tape are drawn from the machine and pasted cross-wise of the box, the weights are shifted and a strip of tape is drawn from the machine to the farther end of the box and, because the box is positioned by the cleats *y* and *z*, the tape will be long enough to overlap the sides as required. The shelf *u* can be adjusted for different sizes of cartons by raising or lowering it as desired.

It will be seen from the foregoing description that the present invention contemplates a bench of peculiar construction adapted to hold different sizes of cartons in such a manner with relation to the material used that the sealing of the cartons may be accomplished in a most efficient manner. The carton is held in such relation to the materials used in sealing that there is little if any lost motion on the part of the operator; the machine for delivering gummed tape being directly in front of the operator so that strips may be pulled therefrom conveniently, the carton being held in such relation to the gummed tape machine that the strip as drawn out is automatically measured by the size of each box, the weights being supported adjacent to the box and in a convenient

position for the operator, and the supply of paste being also located at the most convenient point.

I claim as my invention:

45

1. A device for holding and sealing cartons, combining a stand adapted to support a carton to be sealed, a bench adjacent one side of said stand for supporting a tape-holder, carton-positioning means fixed on 50 said stand, a set of members for supporting cartons of different sizes, and means on each member coöperating with said carton-positioning means and so located that all of the cartons are supported at the same distance 55 from said tape-holder, the distance between carton and tape-holder serving as a measure of the length of tape needed including overlap.

2. A device for holding and sealing cartons, combining a stand adapted to support a carton to be sealed, a bench comprising a portion adjacent one side of said stand for supporting a tape-holder, cleats on said stand, a set of plates for supporting cartons 60 of different sizes, cleats on each plate coöperating with said first-named cleats and so located that all of the cartons are supported at the same distance from said tape-holder, whereby the cartons may be held in predetermined tape-affixing relation to said bench, the distance between carton and tape-holder being equal to twice the overlap of the tape, and the stand being at substantially the 70 height of the top of the carton.

75

In testimony whereof, I have signed my name to this specification, in the presence of two subscribing witnesses.

ARTHUR E. RIDEOUT.
